JOHN NAYDOR, OF LAKEWOOD, OHIO, ASSIGNOR TO NATIONAL CARBON COMPANY, A CORPORATION OF NEW JERSEY.

BRUSH CONNECTION.

1,171,630.

Specification of Letters Patent.

Patented Feb. 15, 1916.

Application filed March 12, 1915. Serial No. 13,866.

To all whom it may concern:

Be it known that I, JOHN NAYDOR, a subject of the Emperor of Austria-Hungary, residing at Lakewood, in the county of 5 Cuyahoga and State of Ohio, have invented a certain new and useful Improvement in Brush Connections, of which the following is a full, clear, and exact description.

This invention relates to fastening connecting cables to electric contacts such as carbon brushes for dynamo electric machines. In such connections flexible copper cables known as "pigtailed" are fastened to brushes in a large variety of ways, for example, by bolting, soldering or riveting. Each of these types are furthermore used in any one of a number of modifications each of which is especially adapted for various uses.

20 My invention relates to an improved type of pigtail connection which is permanently fastened to the brush without the use of solder, bolts, rivets, or by introduction of any additional fastening means for attaching the pigtail to the brush.

In the accompanying drawings and description relating thereto, a method of applying a pigtail without the use of additional elements is disclosed, although it will 30 be understood that my invention is not to be limited to the specific disclosure.

In the drawings: Figure 1 is a cross section through the center of a connection before the end of the cable is spun. Fig. 2 is 35 a similar cross section with the cable drawn into the hole and a tool in position to spin the cable. Fig. 3 shows the brush with the cable spun into the hole. Fig. 4 is a perspective view of one type of finished brush. Fig. 5 is a modified form of connection.

To form a connection the carbon brush 1 has two intersecting passages or holes 2 and 3 drilled therein through which a pigtail 4 is passed. The holes are preferably perpendicular to each other and drilled in the faces as shown, but they could, of course, be drilled in other faces of the brush. The diameter of the opening 2 is slightly larger than the pigtail and the diameter of the passage 3 is made still larger.

In making the connection the cable 4 is pushed through holes 2 and 3 and a coil 5 formed at one end to fit into the hole 3. Instead of forming a coil, the cable may be 55 twisted, splayed out or bunched at one end

in any other manner to fit into the counter sunk portion. After forming the enlarged portion, as in Fig. 1, it is drawn back into the opening 3. The amount of cable that is coiled up will depend on the depth to which the hole 3 is to be filled when completed.

In Fig. 2 the brush is in position to be acted upon by a spinning tool 6 to spin it tightly into the hole. The spinning tool consists of a rod of approximately the same 60 diameter as the hole 3, and is adapted to be rotated rapidly by any means such as a drill chuck 7. The spinning tool simultaneously twists and compresses the fine copper wires of the cable to densely compact them therein and cause them to press into and adhere to the sides of the hole. The spinning tool forces the copper wire down into the hole to a level considerably below the face of the brush and makes a smooth, burnished copper surface. The spun copper strands, in fact, look like a polished, solid copper disk exactly fitted into the hole 3. The amount of material in the coil 5 is preferably made sufficient to give a disk of somewhat greater 65 thickness than the diameter of the hole 2. In making a connection of the form shown, considerable thickness of the disk is desirable, to reduce the resistance and make a strong connection. With a thin brush, a 70 loose coil entirely filling the hole, ordinarily does not give the desired thickness when spun, and in such cases a part of the cable may first be tamped into the opening with an appropriate tool, and the spinning 75 operation performed afterward.

In the form shown in Fig. 5, the unfilled part of the opening 3 is filled with a suitable filling material such as cement 8. Ordinarily this is not necessary, but if an iron, copper, or other current conducting cement is used, the conductivity and mechanical strength is still further increased.

Connections using a spun pigtail are less expensive to manufacture because the drilling involved is no more than is ordinarily required for most connections. The new connection is exceptionally neat in appearance and is adapted for use with practically all types of brush holders. The low resistance which it is found to possess may be attributed to the good contact secured by the combined spinning and pressure forcing the fine copper wires, which are very flexible, into such intimate contact with the carbon 105 110

of the brush that they assume every irregularity possessed by the surface, and in addition some of the strands are forced into the carbon.

3. In some instances it may be considered desirable to under cut the walls of the cavity when the cable is to be compacted, but I find that such is not necessary in the majority of cases.

10. While the connection has been described in regard to a brush, it obviously is applicable to other types of contacts such as switch contacts, resistors, etc.

Having described my invention, what I claim is:

1. The method of attaching a stranded conductor to a brush, which consists in spinning a part of the conductor in an opening in the brush until the strands are forced 20 into a compact mass.

2. The method of attaching a stranded pigtail to a brush, which consists in forming two intersecting channels therein, fitting a coiled end of the pigtail into one of the 25 channels, passing the other end through the other channel and applying a rotating tool to said coil to spin the strands into a compact mass.

3. The method of attaching a stranded conductor to a brush, which consists in drilling 30 two intersecting holes into the same, one being larger than the other to form a seat

for the end of the conductor, passing a stranded conductor through both of said holes, wadding one end of it in the larger hole, and spinning such wadded portion until the strands are compacted into a dense mass and forced into intimate contact with the walls of the hole and with said seat.

4. A brush having a channel therein, one 40 end of a stranded conductor in said channel, said end being wadded and spun into a compact mass with the strands in intimate contact with the walls of the channel.

5. A brush having intersecting channels 45 and a stranded conductor extending into both of said channels with one end spun into intimate contact with the walls of one of the channels.

6. A brush having intersecting channels, 50 one of the channels being larger than the other to provide a seat, a flexible stranded conductor extending through the smaller hole and into the larger, and having a wadded portion spun in intimate contact 55 with the walls of the larger hole and with said seat.

In testimony whereof, I hereunto affix my signature in the presence of witnesses.

JOHN NAYDOR.
